UNITED STATES PATENT OFFICE.

FRED H. WHITE, OF EASTON, AND SAMUEL W. RORK, OF BOSTON, MASSACHUSETTS, ASSIGNORS TO CHICKERING & SONS, OF BOSTON, MASSACHUSETTS, A CORPORATION OF MASSACHUSETTS.

ADJUSTABLE FRICTIONAL SUPPORT FOR PIANO-DESKS, &c.

SPECIFICATION forming part of Letters Patent No. 760,831, dated May 24, 1904.

Application filed June 29, 1903. Serial No. 163,510. (No model.)

To all whom it may concern:

Be it known that we, FRED H. WHITE, residing at Easton, in the county of Bristol, and SAMUEL W. RORK, residing at Boston, in the 5 county of Suffolk, State of Massachusetts, have invented certain new and useful Improvements in Adjustable Frictional Supports for Piano-Desks, &c., of which the following is a specification.

10 This invention relates to the movable desk or front piece forming a part of the casing of an upright piano, said desk filling the opening in the casing above the keyboard and being adjustable so that it can be swung outwardly more or less to vary the volume of 15 tone due to the vibration of the strings of the piano.

The invention has for its object to provide a simple and effective frictional support adapted to hold the desk by friction at various angles, so that it may be drawn outwardly to any desired extent from its closed position, and thus form an opening of any desired area.

The invention consists in the improvements 25 which we will now proceed to describe and claim.

Of the accompanying drawings, forming a part of this specification, Figure 1 represents an edge view of our improved frictional support. Figs. 2 and 3 represent opposite side views of the same. Fig. 4 represents a section on line 4 4 of Fig. 2. Fig. 5 represents a view similar to Fig. 2, showing the adjustable portion of the support in a different position. Fig. 6 represents a section on line 6 6 of Fig. 5. Figs. 7, 8, and 9 represent side views of the chief parts of the support detached. Fig. 10 represents a section on line 10 10 of Fig. 8. Fig. 11 represents a section 40 on line 11 11 of Fig. 9. Fig. 12 represents a front view of a portion of an upright piano the desk of which is provided with supports embodying our invention. Fig. 13 represents a section on line 13 13 of Fig. 12.

45 The same reference characters indicate the same parts in all the figures.

In the drawings, *a* represents the top of the casing of an upright piano, and *a'* represents

one of the vertical end pieces or uprights of the casing.

b represents the desk, which fills the space at the front of the casing bounded by the top, end pieces, and the horizontal portion immediately above the keyboard, said desk being interposed between the strings and hammer 55 mechanism of the instrument and the space in front of the instrument. The desk is hinged or jointed to the uprights *a' a'*, the hinge connection being usually near the upper edge of the desk, so that its lower portion 60 can be swung outwardly toward the front of the instrument. In the construction here represented the desk is hinged to the uprights by means of pins or dowels *c*, one at each end of the desk.

In carrying out our invention we secure to the end portions of the desk at points below the hinge-pins or dowels *c* two sets of adjustable frictional supports constructed as hereinafter described, there being one of said supports at each end of the desk, each being located at the inner side of the desk and arranged to coöperate with a fixed stud *d*, projecting inwardly from one of the uprights *a'*.

The adjustable frictional support of our invention comprises a holder *e*, formed as an ear adapted to be attached to the inner side of the desk, the ears being here shown as provided with a flange *e'*, having holes for the reception of attaching-screws. When the ear 70 is attached to the desk, it projects inwardly therefrom, as indicated in Fig. 13.

f represents a resilient plate, preferably constructed of tempered sheet-steel, said plate being provided on one side with teeth *f' f'*, 85 which are preferably formed by striking up portions of the metal of the plate so as to form a narrow elongated recess upon one side and a correspondingly-formed ridge or projection upon the opposite side.

g represents an arm having a hub portion *g'*, which is interposed between the ear *e* and plate *f* and is provided with a plurality of slots *g*, each adapted to engage one of the teeth *f'*. The hub portion *g'* is interposed between the ear *e* and plate *f*, and said

parts are connected in such manner that the ear and plate exert a frictional binding pressure upon the hub portion of the arm, said pressure being sufficient to retain the arm at 5 various angles, the arm being pivoted to the ear, so that it can be swung thereon. In this embodiment of our invention the ear, plate, and hub are connected by means of a rivet *h*, which is passed through the said parts and 10 has at one end a headed bearing upon the outer side of the plate *f*, its other end being upset upon the outer side of the ear *e*. The plate *f* is secured to the ear *e* in such manner that it is prevented from rotating by means 15 of a pin *i*, which is affixed to the ear near the margin thereof and extends across the hub portion *g*' and is engaged with the plate *f* by entering a recess *i*', Fig. 9, formed in the margin of said plate. The plate *f* is thus prevented 20 from rotating, and its teeth *f*' are therefore held in the proper positions to engage the slots *g*². The hub portion *g*' is provided with a recess to accommodate the pin *i*, the ends *g*³ *g*³ of said recess constituting stop- 25 shoulders which coöperate with the pin *i* in limiting the swinging movement of the arm *g*. The outer portion of the arm *g* is provided with a slot or recess *s*, which receives one of the fixed studs *d*, the arm being preferably 30 provided with wings or flanges *g*⁵, which form relatively wide sides of the slot *s* and prevent the contact of the arm with the stud *d* from cutting into or wearing the latter.

When the desk *b* is closed, as shown in full 35 lines in Fig. 13, the arm *g* projects downwardly in a substantially vertical position from the ear *e* and is yieldingly locked in this position by the engagement of the teeth *f*' *f*' with two of the slots *g*², as indicated in Figs. 40 2 and 4, the locking engagement thus effected being such that the desk cannot be moved outwardly except by the application of sufficient force to spring the tooth-carrying portions of the plate *f* outwardly, as indicated in Fig. 6, 45 thus permitting the teeth *f*' to bear upon the flat side of the hub portion *g*' between the slots *g*² therein, as indicated in Figs. 5 and 6. The outward swinging movement of the desk causes the arm *g* to swing correspondingly on 50 the ear, owing to its engagement with the stud *d*. The outward swinging movement of the desk is limited by the contact of the stoppin *i* with one of the shoulders *g*³, the desk being then in the position indicated by dotted 55 lines in Fig. 13. When the desk is in this position, the teeth *f*' engage the other two slots *g*² in the hub portion, so that the desk is yieldingly locked in its outward position. Provision is thus made for yieldingly locking the 60 desk in two positions—viz., its closed and its extreme open position. It will be seen, however, that the pressure of the teeth *f*' upon the side of the hub portion *g*' when the arm and desk are in an intermediate position is 65 sufficient to yieldingly retain the arm and desk

in any position between the two. (Shown in Fig. 13.)

In case the desk is relatively light the teeth *f*' and slots *g*² may be dispensed with, the binding pressure of the ear *e* and plate *f* against the 70 sides of the hub portion being sufficient to retain the desk in any position to which it may be adjusted.

It will be seen that the described supporting device is of extremely simple and durable 75 construction, it having but three parts in addition to the rivet *h* and pin *i*, all these parts being adapted to be quickly and economically formed by dies from sheet metal.

It is obvious that the device may be used 80 for other purposes, its use not being limited to a support for the desk of a piano-casing.

It will be seen by reference to Fig. 12 that the ear or holder *e*, resilient plate *f*, and arm *g* are located wholly behind the desk and that the stud *d* is affixed to the casing back of the opening and projects behind the desk. This arrangement of parts obviates the necessity of providing between the end of the desk and the corresponding portion of the casing an 85 opening or crevice of sufficient width to receive the arm *g*. The end of the desk can therefore be arranged practically in rubbing contact with the fixed casing *a*'. 90

We claim—

1. An adjustable frictional support comprising a holder adapted for attachment to the part to be supported, a resilient plate connected with the holder, means for preventing the plate from turning or rotating on the holder, and a swinging arm interposed between the holder and plate and frictionally held thereby, said arm being formed to engage a fixed support. 95

2. An adjustable frictional support comprising a holder adapted for attachment to the part to be supported, a resilient plate connected with the holder, means for preventing the plate from turning or rotating on the holder, and a swinging arm interposed between the holder and plate and frictionally held thereby, said arm being formed to engage a fixed support, the said arm and plate having complementary locking members, the member or members on the plate being pressed yieldingly against the arm by the resilience of the plate. 100

3. An adjustable frictional support comprising a holder adapted for attachment to the part to be supported, a resilient plate located beside the holder, a swinging arm interposed between the holder and plate, a rivet engaging the central portions of the holder and plate to bind the same together and hold them in frictional contact with the arm, said rivet constituting the axis on which the arm swings, and a stud connecting the marginal portions of the holder and plate and preventing the plate from moving with the arm. 110

4. An adjustable frictional support com- 115

prising, first, a holder formed as an ear or bracket adapted for attachment to the part to be supported; secondly, a resilient plate having inwardly-projecting teeth; and thirdly, 5 an arm having a slotted outer portion formed to engage a fixed support, and a hub portion interposed between the said ear and plate and provided with slots to engage said teeth, the said ear and plate being connected to prevent 10 rotation of the plate and to exert a yielding frictional hold on the interposed hub portion of the arm.

5. An adjustable frictional support comprising a holder formed as an ear or bracket 15 adapted for attachment to the part to be supported, a resilient plate having inwardly-projecting teeth, an arm having a slotted outer portion formed to engage a fixed support, and

a hub portion interposed between the ear and plate and provided with slots arranged to engage 20 said teeth and with a pair of stop members, a rivet securing said parts together and holding the ear and plate in frictional engagement with the said hub portion, and a stoppin 25 engaged with said ear and plate and preventing rotation of the plate, said pin being interposed between the stop members of the hub portion.

In testimony whereof we have affixed our signatures in presence of two witnesses.

FRED H. WHITE.
SAMUEL W. RORK.
